ABSTRACT OF THE DISCLOSURE

This invention relates to a grinding machine and, more particularly, to apparatus for generating a surface of revolution by the abrasive method including a proximity gage mounted in the wheelhead of the machine and generating a signal indicative of grinding force.

BACKGROUND OF THE INVENTION

In the operation of a grinding machine, there are many advantages to be obtained by regulating the force between the abrasive wheel and the workpiece. In internal grinding (where the abrasive wheel is mounted on a cantilever spindle), the wheelhead spindle when loaded undergoes a radial and an angular deflection. The angular deflection causes taper, if not compensated for, and the radial deflection causes changes in bore size. The presence of these elastic effects complicates the operation and the set-up and this is particularly true of the "feed-rate" grinder. That is to say, even if the operation of the grinding machine is perfect at a given force, these deflections upset the relationships, so that precise control of finished size and taper becomes impossible. Since the advantages of controlled-force grinding are best realized by shifting from one force level to another, it can be seen that the change in angular and radial deflection interfere with precise control of size and taper. These and other difficulties experienced with the prior art devices have been obviated in a novel manner by the present invention. It is, therefore, an outstanding object of the invention to provide a grinding machine arranged so that changes in the grinding force do not cause size or finish stock changes or taper changes.

Another object of this invention is the provision of a grinding machine for use in generating a surface, the operation of the machine being greatly simplified. A further object of the present invention is the provision of a grinding machine in which an unskilled workman need not be concerned about spindle deflections and for readjusting for both size and taper after changing the grinding force.

It is another object of the instant invention to provide a grinding machine in which the grinding force can be changed as the wheel wears to a smaller size, thereby maintaining the proper cutting action and surface finish for new wheels as well as used smaller diameter wheels.

A still further object of the invention is the provision of a grinding machine in which the grinding force can be changed to compensate for wheel dulling and/or variations in workpiece grindability without deterioration of other finished workpiece factors.

It is a further object of the invention to provide an internal grinding machine using a plurality of different grinding force levels wherein compensation is made for radial and angular deflection with changes in force.

With these and other objects in view, as will be apparent to those skilled in the art, the invention resides in the combination of parts set forth in the specification and covered by the claims appended hereto.

2

SUMMARY OF THE INVENTION

In general, the present invention relates to a grinding machine having a base, a workhead mounted on the base and adapted to support a workpiece, a wheelhead mounted on the base and including a rotatable spindle with an abrasive wheel, a proximity gage mounted on the wheelhead or workhead and developing a signal indicative of grinding force, and a control receiving the signal and using it to regulate the relative movement between the workhead and the wheelhead.

BRIEF DESCRIPTION OF THE DRAWINGS

The character of the invention, however, may be best understood by reference to one of its structural forms, as illustrated by the accompanying drawings, in which:

FIG. 1 is a schematic plan view of a grinding machine embodying the principles of the present invention,

FIG. 2 is a perspective view of a wheelhead incorporated in the machine,

FIG. 3 is a horizontal sectional view of the machine taken on the line III—III of FIG. 2,

FIG. 4 is a schematic view of a control apparatus incorporated in the machine, and

FIG. 5 is a graph showing the variation of spindle deflection with force in the case of two typical grinding spindles.

DESCRIPTION OF THE PREFERRED EMBODIMENT

Referring first to FIG. 1, which best shows the general features of the invention, the grinding machine, indicated generally by the reference numeral 10, is shown as having a base 11 having a workhead 12 carrying a workpiece 13 operable for movement longitudinally of the axis of the workpiece in the well-known manner.

Also mounted on the base is a cross-slide 14 arranged for sliding transversely of the axis of the workpiece under the impetus of a feed cylinder 15 which is operable under hydraulic pressure to provide a predetermined level of force in grinding. A position transducer 16 is an instrument of the LVDT type which gives an electrical signal indicative of the position of a movable core. Mounted on the cross-slide for pivotal movement about an axis 17 is a wheelhead 18. The wheelhead is provided with a cantilever spindle 19 which carries on its outer end an abrasive wheel 21 arranged for the generation of a bore in the workpiece 13.

The cross-slide 14 is connected to the base by a dashpot 22 which assures against erratic movement thereof. At the outer end of the wheelhead 18 is located an angular adjusting motor 23 which operates on the wheelhead through a ball screw 24. Connected in the hydraulic line leading to the feed cylinder 15 is an electro-hydraulic valve 25 which is capable of varying the pressure in the feed cylinder in accordance with an error signal introduced to the valve.

FIGS. 2 and 3 show the manner in which a proximity gage 26 is associated with the wheelhead 18 and the spindle 19. A signal lead 27 extends away from the wheelhead and is connected to a non-contacting position transducer, such as the Bentley pickup 28. This equipment is associated with a slinger 29 which surrounds the spindle of the wheelhead as it emerges from the wheelhead. Extending around the slinger is a bronze sensing ring 31 which is fixed to the slinger which, in turn, is fixed to the spindle in the wheelhead. The ring 31 has an outer cylindrical surface 32 and the sensing element of the Bentley pickup 28 lies closely adjacent to this surface. The pickup has the characteristic of giving an electrical signal proportional to the closeness that its sensor lies to a

given surface. Since the spindle 19 is mounted in bearings in the wheelhead, any deflection either radial or angular in the spindle will result in a change in distance between the surface 32 and the sensor of the Bentley pickup 28, thus resulting in a change in electrical signal on the lead 27.

Referring to FIG. 4, it can be seen that a signal proportional to the actual grinding force is compared with a reference signal and the error is fed to the electro-hydraulic valve 25. This valve, in turn, supplies pressure to the feed cylinder of the cross-slide, thereby producing the desired grinding force at the wheel. FIG. 4 is a block diagram of this system. The input voltage is also fed to the positioning motor 23 causing the wheelhead to be swiveled by the proper amount to exactly nullify the angular deflection of the wheel. In order to make the workpiece size independent of grinding force, the feedback signal from the Bentley pickup 28 (the wheelhead dynamometer) is subtracted from the LVDT transducer 16 signal from the cross-slide 14 and is fed to a meter relay 33. The meter relay "fires" at a given voltage level so that, as higher forces are used, the cross slide has to move further to produce the same bore size. The gains K_c and K_g are set to match the deflection characteristics of the wheelhead. With the above system, both the bore size and taper become independent of the grinding force, i.e., programmed changes in grinding force do not affect the bore size or the straightness of the bore.

FIG. 5 is interesting in giving the general picture of the radial and angular deflection in a large and small wheelhead and shaft as the force changes at the grinding wheel. It can be seen, for instance, that a 10 pound force change will cause a little over .0001" change in deflection which means .0002" in diameter change and will result in .0002"/inch taper, so that inaccuracies introduced by relatively small changes in force can be quite appreciable. It can be seen that by use of the present apparatus it is no longer necessary to worry about spindle deflections. It is possible, then, to change the grinding force from one value to another during the grinding cycle without affecting size or taper. This can lead to the concept of programmed force profiles as inputs to the control system. One can have the force built up along some curves, such as the one illustrated in FIG. 4 and to die out along another curve. If the buildup takes place too fast, wheel breakdown can occur during rounding up. If it happens too slowly, of course, it adds to the cycle time. It is, therefore, quite desirable to have complete control of this force profile or the force changes which take place during the grinding cycle. Similarly, we may wish the force to die out along some curve and not to spark out at a rate determined by the spindle stiffness which may consume excess time; at the present time, it is usual practice to terminate the grinding cycle by a sparkout which uses only the accumulated forces due to the deflection of the spindle to cause grinding. It would be possible, therefore, that complete information about the optimum force profile could be punched onto IBM punch cards and this card used as an input to the grinding machine to control the force cycle.

It can be seen, then, that the present apparatus permits changes in grinding force to take place without causing changes in size in the finished workpiece or changes in straightness. It makes it possible to produce internal

grinders whose operation is greatly simplified. An unskilled workman does not have to concern himself about spindle deflections and he does not have to readjust the machine for both size and taper after changing the grinding force. Moreover, the grinding force can be changed as the wheel becomes smaller due to wheel wear and this permits maintaining the proper cutting action and surface finish for new wheels of initial wheel diameter as well as for used worn-down wheels of smaller diameter. It makes it possible to change the grinding force to compensate for wheel dulling and for variations in workpiece grindability. For instance, some workpieces grind much slower than others, even in the same batch of workpieces.

It is obvious that minor changes may be made in the form and construction of the invention without departing from the material spirit thereof. It is not, however, desired to confine the invention to the exact form herein shown and described, but it is desired to include all such as properly come within the scope claimed.

The invention, having been thus described, what is claimed as new and desired to secure by Letters Patent is:

1. A grinding machine, comprising

- (a) a base,
- (b) a workhead mounted on the base and adapted to support a workpiece,
- (c) a wheelhead mounted on the base and including a rotatable spindle with an abrasive wheel,
- (d) a hydraulic cylinder for bringing about a desired grinding force,
- (e) a valve for controlling the flow of fluid to the cylinder,
- (f) a proximity gage mounted so as to develop a signal indicative of grinding force, and
- (g) a control receiving the electrical signal derived from the proximity gage and comparing it with a master signal indicative of the desired force, the error signal derived from the comparison being used to adjust the valve for bringing about the desired grinding force.

2. A grinding machine as recited in claim 1, wherein the proximity gage consists of a ring mounted on the spindle and an electrical proximity element mounted in the wheelhead and having a sensing member lying adjacent the cylindrical surface of the ring.

3. A grinding machine as recited in claim 2, wherein the input signal of desired force level also operates a positioning motor which brings about angular adjustment of the position of the wheelhead relative to the axis of the workpiece.

4. A grinding machine as recited in claim 1, wherein an electrical measuring element derives a signal indicative of the relative position between the workhead and the wheelhead and feeds that signal into the said control for regulating the relative movement between the workhead and the wheelhead.
